MICHAEL J. McCAFFREY, OF NEW YORK, N. Y., ASSIGNOR TO CHARLES E. MILLER AND ROBERT H. BENARY, OF NEW YORK, N. Y.

VARNISHING AND GUMMING MACHINE.

No. 827,934.

Specification of Letters Patent.

Patented Aug. 7, 1906.

Application filed May 19, 1906. Serial No. 317,687.

To all whom it may concern:

Be it known that I, MICHAEL J. McCAFFREY, a citizen of the United States, residing at New York, in the county of New York and State of New York, have invented certain new and useful Improvements in Varnishing and Gumming Machines, of which the following is a specification, such as will enable those skilled in the art to which it appertains to make and use the same.

This invention relates to that class of machinery which is intended for the purpose of covering sheets of paper or similar material with or without printed matter thereon with varnish or with adhesive gum, or with both; and the object of my improvement is to apply the varnish or the gum to the sheets in such a manner so as to regulate the thickness of the film to be applied, a further object being to prevent accidental blots or destructive imprints being transferred to the sheet in said operation from the varnishing-rolls, and a still further object being to provide an effective and novel means for transferring the varnished sheets from the operating varnishing-rolls through the steam drying-box to the take-off table.

The invention is fully disclosed in the following specification, of which the accompanying drawings form a part, in which the separate parts of my improvement are designated by suitable reference characters in each of the views, and in which—

Figure 1 illustrates a diagrammatic view of the entire system of varnishing and gumming, of steam and cool air drying, and the transmission service needed in connection therewith. Fig. 2 is a plan view of one part of the same. Fig. 3 is a side view of the gearing employed with the varnisher; and Fig. 4 shows detail views of an adjustable shaft-bearing used with my improved apparatus.

In apparatus of this class, and particularly referring to the varnishing and gumming transferring-rolls, it has been usual to employ a fountain containing a composition roller in order to dip up the varnish and transfer the same to the sheets to be covered therewith. A metal roller was usually employed which was kept bearing against the composition roller and which was adjusted to the latter so as to determine the thickness

of the film of varnish to be transferred from the fountain onto the sheets. This arrangement does not prevent the transference of spots, smuts, &c., accidentally imparted to the composition roller from the contents of the fountain to the sheets, such spots, smuts, &c., leaving their imprint on the composition roller which in turn transfers the same to the sheet and causes the latter to become useless. In order to obviate this, I provide a fountain *a*, containing the varnish or gum in fluid state, and a metal roller *b* of comparatively large diameter, which is mounted in proper stationary bearings *c* of the main frame of the apparatus, dips into the fountain. Mounted above this metal roller *b* is a composition roller *d* of smaller diameter than the metal roller *b*. This roller *d* rests in vertically-adjustable bearings *e*, also fixed to the main frame of the machine. The metal roller *b*, which rotates in the direction shown in the drawings, will transfer to the composition roller *d* from the fountain *a* sufficient fluid matter to cover its surface with a thin film of gum or varnish while the latter is rotating in the opposite direction, and the thickness of this film can easily and effectively be regulated by the vertical adjustment of the bearings *e*.

At *f* is shown the usual drum around which the sheets are passed and which is provided with the necessary mechanism (not shown in the drawings) to pick up the sheets from the operating-table *g* and draw the same through its contact with the composition roller *d*, whereby the sheets become impregnated with the fluid transferred thereon and which also delivers the varnished sheets *h* to the endless belt *k*, which carries the wet sheets *h* to the usual steam drier *i*.

As seen in Fig. 3, a main driving-belt imparts motion by means of a pulley secured to a shaft *j*, which latter rotates the endless belt *k*. This shaft *j* carries a gear *j'*, which meshes with the gear-wheel *j''*, attached to the shaft of the revolving drum *f*. The gear-wheel *j''* engages with an intermediate gear-wheel *j'''*, which in turn meshes with the gear-wheel *j'''*, fixed to the shaft of the metal roller *b*. The opposite end of said shaft carries a similar gear-wheel which engages with the gear-wheel *j''*, placed on the shaft of the com-

position roller *d*. The belt *k* travels in the direction of the arrows, as shown in Fig. 1 of the drawings, the drum *f* rotates toward the upper layer of the endless belt *k*, the composition roller *d* is rotated in an opposite direction to the drum *f*, and the metal roller *b* revolves in an opposite direction to the latter and in the same direction as the drum *f*, the train of gear-wheels shown in the drawings 10 accomplishing these results.

The adjustable bearing *e* is shown in Fig. 4 and consists of an open framework with a vertically-sliding shaft bearing block *e'*, which can be adjusted by means of the screw *e''* and 15 held in the desired position by the set-nut *e'*, thereby regulating the thickness of the fluid matter to be transferred from the metal roller *b* to the composition roller *d*. By means of this arrangement impurities which 20 inadvertently enter the fluid cannot come in direct contact with the composition roller, nor cannot thereby be transferred to the sheet and become impressed thereon.

The steam drying-box *i* is, as usual, provided with longitudinally-extending steam-pipes *i'*, which provide the necessary drying heat to the wet sheets which are carried into the box by means of the endless belt *k*. This endless belt *k* is preferably made of canvas, 25 of netting, or other suitable material and rests on the bearing-rollers placed under the same and placed within the drying-box at the entrance thereof, as shown at *L*, and at the exit from the drier, as shown at *m*, where 30 three rollers are shown, which will give to the belt *k* a temporary downward motion at this point.

An endless cord *n* encircles the outside of the belt *k* and travels therewith. This cord 40 may be incorporated into the belt *k* and form a part therewith, or it may be strung around the entire belt and sufficiently taut drawn in order to travel with the belt over the rollers whenever set in motion. This cord, as seen 45 in Fig. 2, is placed midway of the belt and has the tendency to keep the sheets *h* at or near the middle of the belt, and especially guides the same downwardly at *m*, where the sheets are deposited upon the second traveling belt *o*. One or more vertically-traveling belts or cords *p*, moving over independent 50 pulleys and placed in front of the delivery end *m* of the drier *i*, also deflect the sheets downwardly toward and upon the second belt *o*, which latter, moving in the direction 55 of the arrows as shown in Fig. 1, conducts the steam-dried sheets *h* back toward the drum *f*, where at the terminal of said belt *o* the sheets are deflected downwardly again at *q* upon a third vertically-traveling belt *r*, which delivers the steam and air dried sheet 60 upon the take-off table at *s*.

At *q* the deflectors may be of any ordinary form, such as a sheet of cardboard or other

suitable material, as the dried and cool sheets *h* brought thereto by the belt *o* follow mechanically and easily the direction of the deflecting-board, but at *m* where the steam-dried and hot sheets leave the drier mechanically active motion must be given to the 70 sheets *h* by the mechanism *p*, as described, in order to deflect the sheet *h* down onto the second belt *o*, for the reason that otherwise the sheet *h* would be drawn again into the drying-box *i* by the adhesive qualities caused 75 by static electricity imparted to the sheet *h* and the belt *k* by the heat of the drier.

It is obvious that the series of endless belts may be increased or decreased to suit the various requirements incidental to the class of 80 work to be performed, the nature of the locality where the apparatus is employed, &c.

By means of this transmission and delivery system I am enabled to perform automatically by means of my improved machinery 85 the entire drying process without the use of manual labor where such help was heretofore employed in this class of machinery, and especially in transferring the sheets from the steam drier to the air drying apparatus at *m* in drawings, and perfect work both as to obtaining the desired thickness of the 90 gum or varnish film and obviating the transfer of destructive spots caused by dirt or smuts in the fountain is effectively attained 95 by the use of my improved roller system, as described in the foregoing description.

Having fully-described my invention, what I claim as new, and desire to secure by Letters Patent, is—

1. In an apparatus of the class described, a set of varnishing and gumming rolls, a steam drier, an endless belt conveying the wet sheets through the steam drier, said endless belts being provided with cords placed centrally thereon and moving with said belt, a set of vertically-traveling belts at the delivery end of the steam drier designed to deflect the sheets when leaving the same onto the series of belts traveling horizontally and in alternate 110 directions in the atmosphere outside of the drier and designed to deliver the steam-dried and air-cooled sheets automatically to the take-off finishing-table.

2. In an apparatus of the class described, a 115 fluid-receptacle, a set of varnishing and gumming rolls consisting of a metal roller which dips up the fluid from the receptacle, and a composition roller placed above the metal roller and out of reach of the fluid-receptacle, 120 and means for regulating the desired space between the metal and the composition roller for the purpose of determining the thickness of the film of the fluid matter to be transferred by the composition roller to 125 sheets to be covered thereby, and a steam drying and air cooling device provided with endless traveling belts so arranged

as to subject the sheets when leaving the varnishing or gumming rolls automatically to a series of trips in alternate directions through the steam drier and through the outer atmosphere prior to their arrival at the take-off table, the endless belt traveling through the steam drier being provided with cords placed centrally thereon and moving said belt.

In testimony that I claim the foregoing as my invention I have signed my name, in presence of the subscribing witnesses, this 17th day of May, 1906.

MICHAEL J. McCAFFREY.
